VENETIAN BLIND CORD PULL

Joseph W. Steinbachner, Chicago, Ill.

Application June 24, 1946, Serial No. 678,993

6 Claims. (Cl. 160—173)

1
The current invention pertains to certain features of novelty and convenience in the manipulation of Venetian-blinds, and it concerns structural advancements and betterments in the terminal pulls attached to the lower ends of the customary pair of hanging cords which control or govern the transverse slopes or tilts of the blades or slats of the blinds.

Heretofore, it has been usual either to employ no such end members or pulls for the cords or to use a pair that are alike for the twin cords, or a chain, so that the operator very frequently inadvertently manipulates the wrong cord rather than the correct one to obtain the desired result.

One object, therefore, of this invention is to provide cord-pulls which can be readily distinguished from one another merely by their manual feel, and, in fact, readily distinguishable from one another even in the dark, a further design of the invention being to supply pulls of this type which by their appearance show which one to pull to get the required tilt or slope of the slats, another goal of the invention being to furnish pulls which are structurally alike but which may be attached to the cords in such a manner that although structurally identical their method of fastening to the cords is such that they are easily differentiated from one another.

Moreover, another object of the invention is to supply the need for pulls for this purpose which are simple in construction, which can be economically produced and sold at a low figure, which are pleasing in appearance, which are of such style that the cords may be attached thereto with facility, which are unlikely to become detached and which may be grasped and pulled by the hand with ease and comfort.

In order that those acquainted with and skilled in this art may readily understand this invention and its inherent advantages both from structural and functional standpoints, present preferred embodiments thereof have been portrayed in the accompanying drawing forming a part of this specification and to which reference should be had in connection with the following detailed description.

In this drawing in which like parts of the appliance have been supplied with the same reference characters throughout the several views:

Figure 1 shows in perspective a portion of a Venetian-blind including that part of its operating mechanism which tilts or transversely adjusts its plurality of slats;

Figure 2 presents an elevation on a larger scale the lower terminal portions of its two cords and

2
their end pulls constituting the present invention;

Figure 3 is a perspective view of one of such pulls;

Figure 4 is a central, longitudinal section through the pull on line 4—4 of Figure 3 including its cord;

Figure 5 is a lengthwise section on line 5—5 of Figure 4; and

Figures 6 and 7 show respectively an elevation and lengthwise section of a modified form of the pull.

As is clearly indicated fragmentarily in Figure 1, the ordinary Venetian-blind slats or blades 10, 10 are supported by webbing 11 which also carries the lower bar 12, such webbing being actuated and controlled by mechanism 13 above, the rocking of the slats on their axes to admit more or less light being governed by a pair of accessible hanging cords 14 and 15 with their lower terminal pulls 16 and 17 which constitute this invention, these pulls being alike but oppositely arranged.

Each such pull is made of any appropriate material, such as molded plastic, in the form of a partial arrow having a pointed or tapered head portion 18 with its converging surfaces 19 and 20 transversely rounded to avoid sharp edges and with its end surface 21 flat.

The short body or stem 22 of the arrow extending from the center of surface 21 is externally cylindrical, such part 22 and the head of the arrow having an aperture 23 extended through the whole length of the partial arrow at about the middle thereof and centrally intersecting a round hole 24 of larger diameter extended through the entire thickness of the arrowhead from front to back and open at both ends.

One of these arrow pulls 16, for example, is applied to the downwardly pullable rope or cord 14 aiming down as shown in all of the figures of the drawing by inserting the lower end of cord 14 through the stem aperture 23, which is of proper size to receive the cord, and into hole 24 from which it can be temporarily withdrawn or extracted sideways by hand through one of the ends of hole 24, whereupon its end can be knotted and the cord then drawn back so that the knot 25 is neatly housed in cavity 24, whereupon the pull is in condition for operating its cord by a downward pull on the arrow, the operator knowing by its shape and feel that that is the proper one to pull to obtain the inward downward slope of the slats of the blind.

The second arrow-pull 17 is in analogous man-

ner applied to the other cord 15, except that the arrow points upwardly by introducing the cord through the head-end of aperture 23 and tying it similarly causing its knot to occupy hole 24 as depicted in Figures 1 and 2.

Thus the operator knows at a glance which arrow to pull to tilt or slope the blades or slats transversely either inwardly downwardly or inwardly upwardly, and the pulls are of such size and shape that their actuation is a matter of ease and convenience rather than one of conjecture as was common occurrence prior to the production of this innovative structure which is especially inexpensive to produce because both arrows are alike, although differently applied to their respective cords.

In Figures 6 and 7 is shown a modified and, at least in some cases, a preferred form of pull which, as indicated hereinbefore, is to be applied to the cord pointing either upwardly or downwardly, the latter condition only being depicted in the drawing since the reverse application will be readily understood.

Insofar as convenient, the reference numerals used in these Figures 6 and 7 are the same as those employed in the other figures plus 100.

In this case, instead of having a round hole 24 through the pull intersecting the aperture 123 which extends longitudinally centrally through the whole length of the pull, the arrow-head, characterized as a whole 118, is divided transversely into two parts, the main body designated 131 and the tip portion identified as 132, the former having a central cylindrical cavity 133, constituting in effect an aligned enlargement of the aperture 123 and near its mouth having a very shallow, circular internal groove 134.

The apertured arrow-tip member 132 has a tapered external surface conforming to and constituting an extension of the outer surface of member 131, such part 132 having a short cylindrical extension designed and adapted to fit snugly in the mouth of the cavity 133 and supplied with a shallow circular rib adapted to be forced into groove 134 and thereby firmly hold the member 132 in place and against removal after the complementary parts 131 and 132 have been applied together in the relation illustrated.

In buying the two pulls for the two cords, the purchaser receives two like members 131 and two like tips 132 wholly separate from the parts 131.

He then applies one of the elements 131 to the end of one cord by feeding it through aperture 123 and into cavity 133. Then he ties the knot 125 in the end of the cord whereupon he pulls the cord back thereby retracting the cord into the cavity, and then he applies the tip member 132 to such part 131 upon completion of which action the knot is wholly concealed and the tip retained in place due to the interfitting of its rib into its accommodating groove 134.

Thus the application of the downwardly-aimed arrow is finished.

To fasten the other pull to the other cord, the latter is fed through the aperture 123 of the remaining tip 132 and the knot tied in its end whereupon the tip is applied to the member 131 with the knot in the cavity 133, thus completing the fastening of such upwardly-aimed arrow pull to the cord, or it may be considered that the member 131 is applied to the knotted cord tip.

The structure presented in Figures 6 and 7 has the advantage that after the pulls have been

applied to the cords the knots of the latter are not visible.

Those acquainted with this art will readily understand that the invention as defined hereinafter is not necessarily limited and restricted to the precise and exact details set forth hereinbefore and in the drawing, and that reasonable modifications may be availed of without departure from the heart and essence of the invention and without the loss of any of its material benefits and advantages.

I claim:

1. A pull for a Venetian-blind hanging cord controlling the transverse slope of the slats of the blind to be manipulated by the cord, said pull having the general form of a tapered direction-indicating arrow-head equipped with a longitudinal central stem, said arrow-head having an externally accessible cavity, the pull having a longitudinal passage extended through said head and stem and intersecting said cavity and of a caliber to receive the lower terminal portion of said cord, whereby said portion of the cord may be inserted in the pull passage through either end of said passage into said cavity, its then accessible end knotted, and said knot occupying said cavity and supporting the pull on the cord.

2. A pull for a Venetian-blind hanging cord controlling the transverse slope of the slats of the blind to be manipulated by the cord, said pull having the general form of a tapered direction-indicating arrow-head equipped with a longitudinal central stem, said head having a hole therethrough from its front to its back and open at both ends, the pull having a longitudinal middle passage extended through said head and stem and intersecting said hole and of a caliber to receive the lower terminal portion of said cord, whereby said portion of the cord may be inserted through either end of said passage into said hole, its then accessible end knotted and the knot occupying said hole and supporting the pull on the cord.

3. A pull for a Venetian-blind hanging cord controlling the transverse slope of the slats of the blind to be manipulated by the cord, said pull having the general form of a relatively large flat tapered direction-indicating arrow-head equipped with a comparatively small, central longitudinal stem, said head having an externally accessible cavity, the pull having a longitudinal middle passage extended through said head and stem and intersecting said cavity and of a caliber to receive the lower terminal portion of the cord, whereby such portion of the cord may be inserted in the pull through either end of said passage aperture into said cavity, its then accessible end knotted, with the knot occupying said cavity and supporting the pull on the cord.

4. On a Venetian-blind having a pair of hanging cords to control by downward pulls thereon the opposite transverse tilts of the blind slats, a pair of like cord pulls with one applied to each cord, each such pull having the general form of a tapered direction-indicating arrow-head equipped with a longitudinal central stem, each said head having a hole therethrough from its front to its back and open at both ends, each said pull having a longitudinal middle passage extended through the head and stem and intersecting said hole and of a caliber to receive the lower terminal portion of one of the cords extending in the pull through either end of said passage into said hole, its end in said hole having been knotted with the knot supporting the

pull on its cord, one of said pulls being on its cord aiming downwardly and the other pull on its cord aiming upwardly to indicate the direction of slope of the slats of the Venetian-blind, depending upon which cord is pulled down.

5. A pair of like Venetian-blind cord pulls adapted to be applied to the terminal portions of two such cords in reverse directions, each such pull having the general form of a direction-indicating tapered arrow-head equipped with a central longitudinal stem, said head having a cavity adapted to accommodate a knot of its cord and said head and stem having a longitudinal aperture open at both ends and intersecting said cavity, the cord entering such cavity in one case through the head aperture and in the other case through the stem aperture.

6. The cord pulls set forth in claim 5, in which each said head is divided into two parts on a transverse plane intersecting said cavity, said two parts being interfittable in a manner to prevent their separation upon actuation of the cord by the pull.
